UNITED STATES PATENT OFFICE.

EDWD. HEATH, OF FOWLERVILLE, NEW YORK.

IMPROVED DITCHING-MACHINE.

Specification forming part of Letters Patent No. 58,413, dated October 2, 1866.

To all whom it may concern:

Be it known that I, EDWARD HEATH, of Fowlerville, in the county of Livingston and State of New York, have invented a new and Improved Ditching-Machine; and I do hereby declare that the following is a full, clear, and exact description thereof, which will enable others skilled in the art to make and use the same, reference being had to the accompanying drawings, forming part of this specification.

The nature of my invention consists in so constructing a machine that the ground may be ditched rapidly and to any desired depth for laying tile for the purpose of draining land.

It more particularly consists in the peculiar and novel manner by which I produce a longitudinal motion to the excavator or digger and a lateral motion to the scraper through the medium of the same cross-head.

It also consists in the novel manner by which the machine is propelled forward by means of the same cross-head.

It has for a long time been the great desideratum of agriculturists and inventors to introduce or devise some means by which lands might be drained and utilized and made valuable and productive. This, to a certain extent, has been accomplished in some localities; but the machines invented and introduced for this purpose have been cumbersome and expensive, so much so that farmers of limited means could not avail themselves of the use of so costly a machine. By my invention these objections and difficulties are overcome, from the fact that there is but little iron required in its construction, and that a common carpenter can build it at an expense of from seventy-five to one hundred dollars, thus bringing it within the reach of farmers of very limited means. The utility and advantages of my invention will be at once seen from the fact that it is well known that lands of a clay soil in their natural state are wet and cold, and are not in a suitable condition to work until late in the season, while the same land drained becomes in a condition to work much earlier, and rendered much more productive than when not drained, by which lands may be reclaimed and made productive and valuable by my invention.

To enable others skilled in the art to make and use the same, I will proceed to describe its construction and operation.

Figure 1 is a top-plan view of my improved ditching-machine. Fig. 2 is a longitudinal vertical sectional elevation taken from the line XX.

Letters of like name and kind refer to like parts in each of the figures.

In Fig. 1, A represents a truck of ordinary construction, mounted on four wheels, B B B B. From near the center of the truck-frame A are two upright posts, upon the top of which is a cross-beam, D, and near the middle of these posts is another cross-beam, E, which runs from post to post, and secured thereto. To these cross-beams is an upright shaft, F, on the top of which is secured a sweep or long lever, G, to which the team is attached to operate the machine. The shaft F runs in proper bearings, at the lower end of which is a crank, H, which is attached to the pitman I at one end, and the other end of the pitman is connected to the cross-head J, which reciprocates on the slides K K.

To the cross-head J are two connecting-rods attached, and extend back and connect with the digger S, the said digger being connected to the frame O, which is attached to a rock-shaft, P, which works upon the uprights Q Q.

On the connecting-rods L L is attached a scraper, R, for the purpose of removing the dirt from the digger as it is brought to the surface of the ground.

Upon the rock-shaft P is a spring catch or latch, T, that at each motion of the digger engages with the digger, and holds it up in its backward motion into the ditch, for the purpose of removing and preventing any loose dirt from falling back into the ditch.

V is also a latch, kept in position by the spring V. W is a scraper, for the purpose of removing the earth from the ditch and leveling the same. This scraper is worked by means of a lug or pin, A², attached to the cross-heads J; said pin A² works against the bars B² and B².

C² is a ratchet-wheel, in which the pawls D² and D³ work. To the shaft of the ratchet-wheel C² is a lever, H², extending down and engages with lugs in the bar. This bar B² is attached to the cross-head J.

The operation consists in placing the machine upon the ground where it is desired a ditch should be made. The team is then attached to the sweeps or arms G. The team then moves in a circle corresponding with the radius of the arms. This puts in motion the cross-head, through the medium of the pitman, which also imparts motion, through the medium of the connecting-rods L L, which are attached to the excavator or digger, the cross-head having a regular reciprocating motion. The cross-head also imparts a lateral motion to the scraper W, through the medium of the bars B² B².

It will be understood that as the cross-head reciprocates, the bars B² B² are caught at the end by the pin A², which, being attached by a joint with the cross-bar of the scraper W, and the scraper is forced one side when on the return of the cross-heads the other bar is brought in such a position by means of the springs, so that the pin engages it, and the scraper is again forced back, so that a continual lateral motion is kept up, and a regular motion is also kept upon the excavator or digger.

The whole machine has a forward movement at every backward movement of the diggers, through the medium of the ratchet-wheel C² and lever H² from the cross-head J.

It will be observed that a chain, N, is fitted to a toothed wheel, I², upon the shaft of the

ratchet-wheel C². The said chain is anchored forward of the machine, and passes from the anchor over the toothed wheel I², and as the chain is drawn by the wheel the whole machine is moved along.

M' is a bridge for the purpose of passing over from one side of the ditch to the other. a a are cutters to cut the earth, so as to prevent the excavator from breaking it up.

Having thus described my invention, what I claim as new, and desire to secure by Letters Patent of the United States, is—

1. A ditching-machine so constructed as that the cross-head will impart a longitudinal motion to excavators and a lateral motion to the scraper at the same time, substantially and for the purposes herein described.

2. The cross-head J, pitman I, and crank H, in combination with the bar E², lever H², and ratchet-wheel C², all for the purposes and substantially as herein set forth.

3. The excavator S and pitmen L L, in combination with the spring-catch T and rock-shaft P, substantially and for the purposes described.

4. The scraper R, in combination with the excavator S, for the purposes and substantially as described.

EDWARD HEATH.
